UNITED STATES PATENT OFFICE.

MAURICE J. WOHL, OF BROOKLYN, NEW YORK.

ARC-LAMP.

1,394,875.

Specification of Letters Patent. Patented Oct. 25, 1921.

Application filed January 14, 1918. Serial No. 211,738.

To all whom it may concern:

Be it known that MAURICE J. WOHL, a citizen of the United States, and resident of Brooklyn, city of New York, county of 5 Kings, and State of New York, has invented certain new and useful Improvements in Arc-Lamps, of which the following is a specification.

This invention relates generally to arc 10 lamps and more particularly to multiple arc lamps in which a unitary mechanism is employed to control several arcs.

The invention has for a general object to provide an improved arrangement of parts 15 for a multiple arc lamp facilitating the direction of the light rays from the arc upwardly, and, if desired, by reason of local operating conditions, laterally.

A further object is to provide an arc lamp 20 in which the source of light may be located at the highest possible point permitted by local conditions.

A further object is to provide an improved unitary control mechanism for a 25 plurality of arcs.

For further comprehension of the invention, and of the objects and advantages thereof, reference will be had to the following description and accompanying drawings, 30 in which latter I have illustrated a preferred embodiment of my invention.

Figure 1 of the drawings is a side elevation of an arc lamp embodying the invention, a portion of the casing being shown in 35 vertical section.

Fig. 2 is a similar view, taken at right angles to Fig. 1, but with the casing and resistances omitted.

Fig. 3 is a horizontal section on the line 40 3—3 of Fig. 1.

Fig. 4 is a horizontal section on the line 4—4 of Fig. 1.

Fig. 5 is a horizontal section on the line 5—5 of Fig. 2.

Fig. 6 is a side elevation of the lamp complete with casing, diffuser and reflector.

Fig. 7 is a detail vertical section on the line 7—7 of Fig. 4.

In the present embodiment of the invention the main frame of my improved lamp includes a series of vertically spaced horizontal disks 2, 3 and 4, the upper and intermediate ones of which, 2 and 3, are relatively close together and are rigidly secured together by the short posts 5. Rigidly fixed at their lower ends in the disk 3 near op-

posite edges thereof are a pair of posts 8 which extend upwardly through the top disk 2 and are fixed at their upper ends to a heavy cross bar 9. On this cross bar may 60 be fixed a bracket 10 carrying a porcelain spool 11 adapted to be engaged by a hook or other member whereby the lamp may be suspended.

The intermediate disk 3 and lower disk 4 65 are rigidly secured to one another by means of a plurality of vertical posts which extend in pairs therebetween. In the drawings these pairs are numbered, respectively, 15, 16, 17 and 18 (see particularly Fig. 5), 70 these posts having a function apart from connecting the disks 3 and 4, as will be presently set forth.

In the present embodiment of the invention four different carbon pairs, and, consequently, four arcs, are provided, and these are controlled by a pair of solenoids, each solenoid controlling two arcs. The different carbon pairs are indicated generally by the numerals 20, 21, 22 and 23, while the 75 solenoids are numbered 24 and 25, the solenoid 24 controlling the carbon pairs 20 and 21, and the solenoid 25 controlling the carbon pairs 22 and 23. The solenoids I have here shown as depending from the 80 intermediate disk 3, being held between the upper plates 30 and lower plates 31 which are secured to rods 32 fixed at their upper ends in the disk 3. These rods extend downwardly and have cross-bars 33 fixed to their 85 lower ends, each of these cross bars having a dash pot 34 mounted thereon coaxially with the respective solenoids.

Resilient connections are preferably provided between the plungers 36 of the dash 90 pots and the cores 37 of the solenoids by vertically spaced and horizontally extending flat springs 38 and 39 connected, respectively, midway between their ends, to the upper ends of the plungers 36 and the 95 lower ends of the cores 37 and secured together at their ends, as by the studs 40.

Secured to the upper ends of the cores 37 are rods 42, preferably of brass or other non-magnetic material, and which extend 100 upwardly, through suitable openings 43 in the intermediate disk 3, into the space between the latter and the top disk 2.

The upper ends of these rods 42 are secured to yoke-bars 44 midway between the 110 ends of the latter, to which yoke-bars are connected the upper ends of links 45 whose

lower ends are connected to clutches 46 of usual construction. I prefer to provide resilient connections between the rods 42 and yoke bars 44, these connections here comprising the springs 48 and 49, similar to the springs 38 and 39, to which the rods 42 and yoke-bars 44 are respectively connected. Fixed at their lower ends to the yoke-bars 44, co-axially with the rods 42, are short 10 steady-ing rods 50 which project upward through suitable openings in the top disk 2.

In the present embodiment of my invention the clutches 46 do not directly engage the carbons of the lamp but engage instead 15 auxiliary rods 55, which I term dummy carbons, and which are mounted at their lower ends in cross heads 57 slidable on the frame-rod pairs 15, 16, 17 and 18. These dummy carbons extend freely upward through the 20 disks 2 and 3, the former of which serves as a guide therefor, and have secured to their tops the lateral arms 58 carrying at their ends carbon sockets 59 of usual construction which are adapted to receive the 25 upper or adjustable carbons. Secured to the top disk 2 in vertical alinement with the carbon sockets 59 are sockets 60 of usual construction adapted to receive the lower or fixed carbons.

30 As will be obvious from the above description and drawings, there are a pair of yoke-bars 44, one connected to each solenoid, and each yoke-bar has connected thereto a pair of the clutches 46, one at each end, each 35 clutch engaging a dummy carbon. There are thus four dummy carbons, one for each carbon pair. The carbon pairs, it will be noted, are disposed above, and radially outward of the control mechanism.

40 The resistances with which arc lamps are provided I have shown at 65 depending from the bottom disk 4, these resistances being constructed in a well known manner by winding suitable wire upon porcelain 45 spools.

The mechanism contained below the intermediate disk 3 is preferably inclosed by a casing 66 secured in position in any suitable manner. In the present instance a bolt 67 50 depends from the bottom disk centrally of the latter and passes through a suitable opening in the bottom of the casing and has a nut 68 screwed on its lower end.

To give a proper diffusion of the light 55 from the arcs I preferably surround the latter with a screen 70 of light diffusing material in the form of an inverted truncated cone, the lower end of which closely, yet freely incloses the casing 66 near the top of the latter while a substantially saucer shaped reflector 71 is placed above the lamp, the latter being conveniently hung to the reflector by a detachable hook, indicated at 72, while the screen 70 may be suspended from 60 the reflector by the chains 73. The screen 65

70 may be conveniently formed of woven ground glass cloth mounted on a suitable frame 79.

With this arrangement a clear and well diffused light, free from shadows, is obtained while the relative arrangement of control mechanism, arcs and reflectors enables the source of light to be placed close to the ceiling when desired.

I have not deemed it necessary to illustrate the wiring circuits, the circuit preferably being downwardly through one pair of carbons, through the controlling solenoid therefor, through the resistance and downwardly through the other pair of carbons controlled by this solenoid, a corresponding circuit being formed in the other unit consisting of two pairs, solenoid and resistance, while the two units may be connected in series or parallel. It will be obvious that 85 flexible connections will lead to the upper carbon sockets to accommodate vertical movement of the latter.

What I claim is:

1. An arc lamp having a frame consisting 90 of a pair of horizontally disposed and vertically spaced disks, a solenoid located under and secured to the lower disk and having its core extending upward through the latter, a clutch disposed above and adjacent the 95 lower disk, an operative connection between said clutch and the said core, a pair of rods extending rigidly downward from the lower disk, a crosshead slidable on said rods, a dummy carbon fixed at its lower end to said crosshead and extending upward through the said disks and being guided by the upper disk, said dummy carbon being in engagement with the said clutch, and a pair 100 of carbon sockets carried respectively by the upper end of said dummy carbon and by one of said disks.

2. An arc lamp having a frame comprising 105 three horizontally disposed and vertically spaced disks, solenoids secured to the underside of the intermediate disk, a series 110 of rods arranged in pairs rigidly connecting the lower and intermediate disks, a crosshead slidable on each pair of said rods, dummy carbons extending upwardly from 115 said crosshead and guided by the upper disk, dash pots each having its plunger connected to the lower end of a solenoid core, clutches 120 engaging the dummy carbons, yokes connecting the said clutches in pairs, said yokes being carried by the upper ends of the solenoid cores, and upper and lower carbon 125 sockets carried respectively by the upper ends of the dummy carbons and the frame of the arc lamp.

Signed at city of New York, county of Kings and State of New York, this 7 day of Jan., 1918.

MAURICE J. WOHL.
